WITNESS:

UNITED STATES PATENT OFFICE.

JOSEPH B. MILTON, DECEASED, LATE OF ENID, OKLAHOMA; BY LUCILE V. MILTON, ADMINISTRATRIX, OF ENID, OKLAHOMA.

GRAVITY LOCK.

Application filed May 23, 1923. Serial No. 641,021.

To all whom it may concern:

Be it known that JOSEPH B. MILTON, deceased, late a citizen of the United States, residing at Enid, in the county of Garfield 5 and State of Oklahoma, has invented new and useful Improvements in Gravity Locks, of which the following is a specification.

This invention relates to improvements in locks and has for an object the provision of 10 a gravity lock which is especially adapted for locking railway switches, the present invention being an improvement upon patent numbered 1,447,144, granted to me February 27, 1923.

Another object of the invention is the provision of a simple and positive lock for this purpose which cannot be operated to release the switch without the use of a special key, so that tampering with the switch by un- 15 authorized persons will be prevented.

With the above and other objects in view, the invention further includes the following novel features and details of construction, to be hereinafter more fully described, illustrated in the accompanying drawings and pointed out in the appended claims.

In the drawings:

Figure 1 is an elevation showing a fragmentary portion of a switch stand with the 30 invention applied thereto.

Figure 2 is a plan view of the same.

Figure 3 is an enlarged vertical sectional view through the lock showing the operating arm in switch locking position.

Figure 4 is a similar view showing the arm in unlocked position.

Figure 5 is a horizontal section on the line 5—5 of Figure 3.

Figure 6 is a vertical section taken substantially on the line 6—6 of Figure 3.

Figure 7 is a detail perspective view of one of the tumblers.

Referring in detail to the drawings wherein like characters of reference denote corresponding parts, the reference character 10 indicates a switch stand which supports a pivotally movable housing 11, the latter being movable over a plate 12 and connected to a switch operating means by a shaft 13.

This shaft passes through and engages the rectangular walls of an opening 14 and may carry at its upper end a signal or indicating element 15.

Pivottally mounted within the housing 11 55 as shown at 16 is an operating arm 17, the

latter being adapted when swung downward to the position shown in Figure 1, to engage either one of a pair of notches 18, the said notches being disposed at 90 degrees with respect to one another. When the arm 17 60 is engaged with the notches 18, the switch will be held in either open or closed position, depending upon the particular notch engaged.

Located within the housing 11 is a pair 65 of tumblers 19 and 20, the first mentioned tumbler surrounding a stud 21 and being provided with a sleeve extension 22, while the tumbler 20 is pivotally mounted upon the sleeve extension 22 and is capable of 70 movement thereon independently of the tumbler 19. The tumblers are thus pivotally mounted so that when the operating arm is in the position shown in Figure 3 one of their ends will drop by gravity into the 75 path of the said arm and lock the same within one of the notches 18.

Pivottally mounted within the housing above the tumblers as shown at 23 is what may be termed a locking plate, the said plate 80 being indicated at 24. This plate is substantially triangular and is provided at one end with an offset shoulder 25 which is adapted to engage a pin 26 projecting from one face of the tumbler 20, thus when the tumbler 20 is moved pivotally in a direction away from the arm 17, its movement will be limited so that it cannot entirely move out of the path of this arm.

The tumbler 20 and the sleeve 22 are provided with arcuate recesses 27 and 28 respectively which are adapted to receive the bit of a key, while the plate 24 is provided with a notch 29 which receives the stud 21 and provides a key bit engaging portion 30. 90 This portion 30 is arranged substantially central between the ends of the recesses 27 and 28 so that the bit of the key will first engage this portion 30 and move the plate pivotally before any movement is imparted to the tumblers. Continued movement however will cause this bit to engage the ends of the recesses, but before this occurs, the plate will have been sufficiently moved to bring the open end of the notch 31 into position to receive the pin 26 so that continued movement of the plate will also move the tumblers to a position out of the path of the arm 17. The latter may then be moved 100 pivotally past the curved edges 32 of the 105 110

tumblers 19 and 20. During this movement the arm 17 will engage a dog 33 which is pivotally mounted upon a pin 34. One end of this dog engages one end of each of the 5 tumblers 19 and 20 and when the dog is moved to the position shown in Figure 4 of the drawings by the operation of the arm 17, the said dog will hold the tumblers out of the path of the said arm until the latter 10 has been returned to its switch locking position.

In order to prevent the insertion of a tool or instrument upward within the housing 11 to operate the locking plate 24, the dog 20 15 is provided with a longitudinally extending laterally offset portion 35 which extends over the edge of the dog and acts to protect the same.

The invention is susceptible of various 20 changes in its form, proportions and minor details of construction and the right is herein reserved to make such changes as properly fall within the scope of the appended claims.

25 Having described the invention what is claimed is:—

1. A switch lock comprising in combination with a pivotally mounted operating arm, a key operated pivotally mounted 30 tumbler having one end normally disposed in the path of movement of said arm, a key operated pivotally mounted locking plate, interlocking means between the tumbler and plate to limit the range of movement of said tumbler, means whereby the plate may be independently moved to increase the range of movement and permit the tumbler to be moved out of the path of the operating arm and means engaged 40 by the operating arm to hold the tumbler in an inactive position.

2. A switch lock comprising in combination with a pivotally mounted operating arm, a key operated pivotally mounted tumbler having one end normally disposed in the path of movement of said arm, a key operated pivotally mounted locking plate, interlocking means between the tumbler and plate to limit the range of movement of said 50 tumbler, means whereby the plate may be independently moved to increase the range of movement and permit the tumbler to be moved out of the path of the operating arm and a pivotally mounted dog having 55 one end engaging the tumbler and the other end arranged for engagement by the arm to hold the tumbler in an inactive position.

3. A switch lock comprising in combination with a pivotally mounted operating arm, a pair of concentrically pivoted independently movable key operated tumblers having one of their ends normally disposed in the path of movement of said arm, a key operated pivotally mounted locking plate, interlocking means between one of the tumblers and the plate to limit the range of movement of said tumbler, means whereby the plate may be independently moved to increase the range of movement of the interlocked tumbler and permit of the tumblers being moved out of the path of the operating arm and means engaged by the operating arm to hold the tumblers in an inactive position. 60 65 70

4. A switch lock comprising in combination with a pivotally mounted operating arm, a key operated pivotally mounted tumbler having one end normally disposed in the path of movement of said arm, a key operated pivotally mounted locking 80 plate, a pin carried by the tumbler, a shoulder provided upon the plate and engaging the pin to provide interlocking means between the tumbler and plate and limit the range of movement of said tumbler, means whereby the plate may be independently moved to increase the range of movement and permit the tumbler to be moved out of the path of the operating arm and means engaged by the operating arm to hold the 85 90 95 tumbler in an inactive position.

5. A switch lock comprising in combination with a pivotally mounted operating arm, a key operated pivotally mounted tumbler having one end normally disposed in the path of movement of said arm, a key operated pivotally mounted substantially triangular locking plate having a notch in one edge thereof, a shoulder provided on the plate adjacent the notch, a pin carried by the tumbler and engaging the shoulder to prevent movement of said tumbler in one direction independently of the plate, but permitting independent movement of the plate, whereby the pin may 100 105 enter the notch and the tumbler move out of the path of the arm and means engaged by the operating arm to hold the tumbler in an inactive position.

In testimony whereof I affix my signature.

LUCILE V. MILTON.
Administratrix for the estate of Joseph B. Milton, deceased.
